UNITED STATES PATENT OFFICE.

JAMES B. DAVIS, OF EUREKA SPRINGS, ARKANSAS.

BAND-CUTTING FEEDER FOR THRASHING-MACHINES.

SPECIFICATION forming part of Letters Patent No. 325,736, dated September 8, 1885.

Application filed July 22, 1884. (No model.)

To all whom it may concern:

Be it known that I, JAMES B. DAVIS, a citizen of the United States, residing at Eureka Springs, in the county of Carroll and State of 5 Arkansas, have invented a new and useful Band-Cutting Feeder for Thrashing-Machines, of which the following is a specification, reference being had to the accompanying drawings.

10 This invention relates to band cutters and feeders for thrashing-machines, and is an improvement on Letters Patent No. 199,172, granted to Henry K. Andrews, January 15, 1878. In said patent only one cutter and feeder is employed; consequently the machine is intended to feed only one sheaf at a time. Practice has demonstrated that such a construction will not cut the bands and feed the grain upon the carrier in a satisfactory manner; and 20 for the purpose of remedying the various defects in the construction shown in said patent I have devised certain improvements, which will make the operation of the machine a success in every particular.

25 The said invention consists in certain details of construction and combination of parts, hereinafter set forth, and particularly pointed out in the claims.

In the accompanying drawings, Figure 1 is 30 a perspective view of my improved band-cutter and feeder. Fig. 2 is a side view, showing the side opposite to that illustrated in Fig. 1. Fig. 3 is a longitudinal sectional view. Fig. 4 is a transverse section on the line $x-x$, Fig. 35 3. Fig. 5 is a transverse section on the line $y-y$, Fig. 2. Fig. 6 is a detail view of one of the cutters, showing the manner of securing the knives in place.

The same letters are used to indicate corresponding parts in the several figures.

40 Referring to the drawings, A designates the frame, consisting of the base-board a and side boards, a' , erected upon the base-board at the exit end of the machine, legs a^2 a^2 being 45 attached to the base-board at the feed end, so as to give a downward-inclination toward the discharge end and thus facilitate the feeding of the grain. The frame is adapted to be placed on the feed-board of the thrashing-machine, and is provided at the discharge end with 50 curved plates D D, to be secured to the sides of the thrasher to hold the machine steady and in

place. Shafts B B' are journaled in the under side of the base-board, at the ends thereof, and provided with flanged pulleys C C, around 55 which pass the belts c' of the carrier E, cross-bars c^2 connecting the belts, and the flanges on the rollers or pulleys serving to prevent the lateral displacement of the carrier when the machine is in operation. I do not limit myself to this special construction of carrier, as various modifications may be resorted to without departing from the spirit or scope of my invention.

F F' designate spring-metal standards attached, at their lower ends to the base-board a of the frame at the feed end of the machine and projecting upwardly, and secured at their upper ends to the sides of guide-boards G G, the latter being inclined, as shown, and supported solely by the spring-standards on each side of the frame above the carrier, so that should a sheaf be fed to the machine which is larger than the ordinary size the guide-boards will yield outward, by reason of the flexibility 75 of the springs, and permit the passage of the same, and thus all danger of clogging will be obviated. A vertical guide-board, H, is arranged between the inclined guide boards G, above the carrier, and is supported in place 80 by braces I I, attached to the outer end, and curved spring-supports J J, secured to the inner end, the ends of the braces I being adjustably attached to the sides of the base-board a , while the ends of the spring-supports 85 J are connected to the side boards, a' . The said spring-supports not only serve as a means of attachment for the dividing or vertical guide-board, but by reason of their peculiar form they prevent the sheaves from scattering 90 or working upward as the bands are cut.

K designates a revolving shaft journaled in bearings in the side boards, a' , and provided at one end with a pulley, d, connected by a belt, L, with a pulley, f, on the outer end of 95 shaft B', and having at the other end a pulley or band wheel, M, to which motion may be imparted by a suitable belt from the thrasher, or by other suitable driving means. Two cutter heads or burrs, N N, are secured on the 100 shaft K at suitable distances apart, so as to come in direct line with the feeding-chutes O O, formed by the guide-boards G G H, said heads or burrs comprising half-sections i i,

formed on their inner adjacent faces with dovetail slots or grooves $m m$, to receive the knives $n n$, the latter having their inner ends correspondingly dovetailed to fit the slots closely, 5 so that when the half-sections of the burrs or heads N are bolted together the knives will be held securely in place and cannot fly out when the machine is in motion. As seen, the outer ends of the knives are curved outward to a 10 point, the sharpened edges of the knives facing the chutes and the shaft K turning the same in a forward direction, so as to cut the bands of the sheaves as the latter are fed along by the carrier.

15 $O' O'$ designate parallel bars extending transversely across and connecting the upper edges of the side boards, a' , the inner sides of the bars $O' O'$ being beveled or cut away to form ways r and receive the slotted extended ends 20 P of a spreader-frame, Q , the latter being arranged between the bars $O' O'$, and adapted to be reciprocated from one side board, a' , to the other. The said spreader consists of the extended ends P , connected by longitudinal bars 25 s , to which is secured a perforated plate, t , a pin, u , on the end of a pitman, R , passing through the perforation of said plate and secured therein. The other end of said pitman connects with a crank, v , on the upper end of 30 a shaft, S , working through a bracket-plate, T , attached to one of the side boards, a' , the lower end of the shaft being journaled in an extension, U , of the side board. A gear-wheel, V , is mounted on the lower end of the shaft, 35 and engages with another gear-wheel, W , which works through a slot, w , of the extension U , the latter wheel, W , being mounted on one end of a shaft, X , journaled to the under side of the base-board. Said shaft X is provided at 40 its other end with a band-wheel, Y , connected by a belt, Z , with a pulley or band wheel, A^2 , on the end of shaft B' , so that the rotation of this band-wheel, caused by the movement of the carrier, effects, by the intermediate mechanism 45 described, the reciprocating movement of the spreader-frame. A series of spreading-rods, $g g'$, are secured to the frame, and extend or curve downwardly and then forward, the rods g being arranged in rear of the large rods g' , and of a much less curvature, the said spreading-rods being adapted to scatter or spread the straw over the entire surface of the carrier preparatory to depositing the same into the 50 thrasher.

55 It will be seen that the base-board a is cut away at h to receive the flanged pulleys C , the carrier working at the ends of the machine over the portion of the base-board intermediate of the pulleys, and guided by the flanges 60 of the pulleys in its movements, so that said carrier will always work true and correct.

The parallel bars $O' O'$ should be either constructed of steel or have their inner sides forming the ways r faced with the same material.

65 The operation of this invention will be readily understood from the foregoing description, taken in connection with the annexed draw-

ings. Motion is imparted to the machine by the belt from the thrasher, causing the shaft K to revolve, which revolution is transmitted 70 to the carrier by the pulleys $d f$, connected by the belt L , and by the movement of the carrier the shaft B' , together with the intermediate mechanism hereinbefore described, causes the spreader to move laterally along the ways 75 r of the bars $O' O'$. Thus the movement of the carrier effects the movement of the spreader, so that when the carrier stops the spreader will cease moving likewise. The sheaves are introduced into the feeding-chutes $O O$ between the adjustable guide-boards, and by the movement of the carrier they are drawn forward under the cutters, the knives of which revolve forward to cut the bands, allowing the sheaves to separate, the feeding of the separated grain being kept up so as to pass under the spreading-rods of the spreader to scatter or spread the straw or grain over the entire surface of the carrier, and then feed the contents of the carrier to the thrasher in the manner well known in the art. 80

It will be seen that by employing the double arrangement of feeding-chutes and cutters I am enabled to perform the work with more satisfactory results than heretofore. The flexibility of the guide-boards allows the passage of sheaves of varying sizes, and the curved spring-supports prevent the sheaves from working upward while being acted upon by the knives. The operation of the spreader is 90 also more effective in its results, causing the thorough scattering of the grain over the carrier preparatory to depositing the same in the thrasher. 95

The improved band-cutter and feeder is 105 simple in construction, can be manufactured at a slight cost compared to others of its kind, and works efficiently and cannot work out of order.

Having described my invention, I claim— 110

1. In a band-cutter and feeder, the combination, with the carrier, of the double arrangement of feeding-chutes, comprising the inclined guide-boards and springs, whereby they are supported above the carrier at each 115 side of the frame, the vertical guide-board arranged between the inclined guide-boards, and spring-rods supporting said vertical guide-board, as set forth.

2. In a band-cutter and feeder, the combination, with the frame, of the spring-supported inclined boards G , the vertical guide-board H , arranged between the same, spring-braces attached to the frame and secured to one end of the vertical guide-board, and curved 125 spring-supports attached to the other end of the said vertical board and adapted to prevent the sheaves from working upward while being acted upon by the cutters, as set forth.

3. In a band-cutter and feeder for thrashing-machines, the combination, with the frame, of the spring-supported inclined guide-boards, the vertical guide-board arranged between the inclined boards, and spring-rods supporting 130

- said boards, the revolving shaft carrying the cutters thereon, which are arranged in line with the chutes formed by the guide-boards, the carrier, and the spreader, as set forth.
- 5 4. In a band-cutter and feeder for thrashing-machines, the combination of the supporting frame-work and endless apron or rake, the band-cutting knives, and a swinging board arranged centrally above the apron or rake, 10 lengthwise of the same, and between the support of the knives and the outer end of the carrier-frame, as set forth.
5. In a band-cutter and feeder for thrashing-machines, the receiving-hopper constructed 15 with a central partition dividing it into sheaf-compartments, and laterally-yielding side boards, as set forth.
6. The herein-described spreader, comprising longitudinal bars, slotted extended end 20 bars connecting the longitudinal bars, ways or guides for the end bars to work in, spreading-rods attached to the bars and curving downwardly and forward, and operating means for the spreader, as set forth.
- 25 7. In a band-cutter and feeder, the combination, with the frame, of the spring-supported inclined guide-boards, and the spring-supported vertical guide-board arranged between the same to form the double arrangement of chutes, the revolving shaft carrying 30 the cutters, curved spring-supports extending over the inner end of the chutes adjacent to the cutters, so as to prevent the sheaves from working upward while being acted upon by 35 the knives, the carrier, and the reciprocating spreader working laterally in guides or ways from one side of the frame to the other to scatter the grain entirely over the surface of the carrier, as set forth.
8. In a band-cutter and feeder for thrashing-machines, the combination, with the frame, of the inclined and vertical guide-boards, forming the double chutes, the revolving shaft carrying the cutters, the carrier, the reciprocating spreader, comprising a suitable frame 40 having slotted extended ends and the spreading-rods, bars attached to the frame of the machine and forming ways or guides for the slotted ends of the spreader, and operating means for the same, as set forth.
9. In a band-cutter and feeder for thrashing-machines, the combination, with the frame, of the double arrangement of chutes and cutters, the carrier, side boards erected upon the frame, bars attached to the side boards, a 45 reciprocating spreader-frame working between the bars, and the spreading-rods attached to the frame, one series of the rods being arranged in rear of the other and having a much 50 less curvature, as set forth.
10. In a band-cutter and feeder, the combination, with the band-cutting mechanism, of the reciprocating spreader-frame working laterally across the carrier from one side to the other between ways or guides and carrying 55 the spreading-rods, one series of the latter being in rear of the other, and shorter and having a much less curvature than the same, as set forth.

In testimony that I claim the foregoing as 70 my own I have hereto affixed my signature in presence of two witnesses.

JAMES B. DAVIS.
